Primary Examiner—Mimosa De(74) Attorney, Agent, or Firm—Baker, Donelson, Bearman, Caldwell & Berkowitz, PC; Lea H. Speed; Peter L. Brewer(57) CLAIMI claim the ornamental design for a tree stand, as shown and described.

DESCRIPTION

FIG. 3 presents a first side view of the tree stand of FIG. 1, once again in its folded out position.

FIG. 4 presents a second opposing side view of the tree stand of FIG. 1 in its folded out position.

FIG. 5 is a bottom view of the tree stand of FIG. 1 still in its folded out position. The support bar is again shown in broken lines.

FIG. 6 provides a rear view of the tree stand of FIG. 1. The tree and support strap are not shown.

FIG. 7 provides a front view of the tree stand. In this view, the tree and support strap are not shown.

FIG. 8 presents a rear view of the tree stand of FIG. 1. Here, the tree stand is in a folded position. The tree stand is strapped onto an individual, shown in broken lines. The individual's profile, of course, forms no part of the claimed invention; and,

FIG. 9 demonstrates a rear view of the tree stand of FIG. 6. In this view, the tree stand is again shown folded out and placed against a tree for use. The tree and support strap are shown in broken lines and do not form a part of the claimed invention.
